Primary Examiner — T Chase Nelson(74) *Attorney, Agent, or Firm* — Marshall A. Lerner; Brad Mattes; Kleinberg & Lerner, LLP(57) **CLAIM**

The ornamental design for an outsole, as shown and described.

DESCRIPTION

FIG. 1 is a bottom plan view of an outsole showing my new design;

FIG. 2 is a right side elevation view thereof;

FIG. 3 is a left side elevation view thereof;

FIG. 4 is a rear side elevation view thereof;

FIG. 5 is a front elevation view thereof; and

FIG. 6 is a bottom plan view of an outsole, showing the claimed design of the preceding figures within a different and larger environment in condition of use.

FIG. 7 is a bottom plan view of a second embodiment of an outsole showing my new design;

FIG. 8 is a right side elevation view of the embodiment shown in FIG. 7;

FIG. 9 is a left side elevation view of the embodiment shown in FIG. 7;

FIG. 10 is a rear side elevation view of the embodiment shown in FIG. 7;

FIG. 11 is a front elevation view of the embodiment shown in FIG. 7; and,

FIG. 12 is a bottom plan view of an outsole, showing the claimed design of the preceding FIGS. 7-11 within a different and larger environment in condition of use.

The broken lines shown in the drawings represent portions of the outsole that form no part of the claimed design.
